SHEET GLASS

Filed Dec. 3, 1930

Inventor:

Conrad J. Gundlach,

By *Cooper, Kerr & Dunham,*
Attorneys.

UNITED STATES PATENT OFFICE

CONRAD J. GUNDLACH, OF NEW YORK, N. Y., ASSIGNOR TO MISSISSIPPI GLASS COMPANY, OF NEW YORK, N. Y., A CORPORATION OF NEW YORK

DESIGN FOR SHEET GLASS

Application filed December 3, 1930. Serial No. 37,867. Term of patent 14 years.

To all whom it may concern:

Be it known that I, CONRAD J. GUNDLACH, a citizen of the United States, residing at New York, in the county and State of New York, have invented a new, original, and ornamental Design for Sheet Glass, of which the following is a specification, reference being had to the accompanying drawing, forming part thereof, in which the figure is a plan view of the article, showing my new design.

The ornamentation shown is continued throughout the respective panels.

The dominant features of the design are the panels with the relatively fine markings presenting a diffusion effect and the relatively narrow sections having a hammered or peened appearance separating said panels.

I claim:

The ornamental design for sheet glass, substantially as shown and described.

CONRAD J. GUNDLACH.
